DESIGN FOR A PIPE RACK

James V. Vevirit, Lewiston, N. Y., assignor to
McDonald Products Corporation, Buffalo,
N. Y.

Application May 16, 1941, Serial No. 100,984

Term of patent 7 years

To all whom it may concern:

Be it known that I, James V. Vevirit, a citizen of the United States, residing at Lewiston, in the county of Niagara and State of New York, have invented a new, original, and ornamental Design for a Pipe Rack, of which the following is a specification, reference being had to the accompanying drawing, forming part thereof.

Figure 1 is a perspective view, looking down-

wardly towards one corner, of the pipe rack, showing my new design; and

Figure 2 is a perspective view of the same, looking upwardly from below the bottom.

I claim:

The ornamental design for a pipe rack, as shown.

JAMES V. VEVIRIT.
